(57) **CLAIM**

The ornamental design for a freestanding payment terminal, as shown and described.

DESCRIPTION

FIG. 1 is a perspective view of one embodiment of a new design of a freestanding payment terminal;

FIG. 2 is a front view of the freestanding payment terminal of FIG. 1;

FIG. 3 is a right view of the freestanding payment terminal of FIG. 1;

FIG. 4 is a left view of the freestanding payment terminal of FIG. 1;

FIG. 5 is a back view of the freestanding payment terminal of FIG. 1;

FIG. 6 is a top view of the freestanding payment terminal of FIG. 1;

FIG. 7 is an enlarged perspective view of a portion of the freestanding payment terminal of FIG. 1;

FIG. 8 is a perspective view of another embodiment of a new design of a freestanding payment terminal;

FIG. 9 is a front view of the freestanding payment terminal of FIG. 8;

FIG. 10 is a right view of the freestanding payment terminal of FIG. 8;

FIG. 11 is a left view of the freestanding payment terminal of FIG. 8;

FIG. 12 is a back view of the freestanding payment terminal of FIG. 8;

FIG. 13 is a top view of the freestanding payment terminal of FIG. 8; and,

FIG. 14 is an enlarged perspective view of a portion of the freestanding payment terminal of FIG. 8.

The broken lines in the drawings form no part of the claimed design.
